UNITED STATES PATENT OFFICE.

JULIUS A. PICKENS AND WALTER F. HESTER, OF EASLEY, SOUTH CAROLINA.

ELEVATOR MECHANISM.

1,342,596.

Specification of Letters Patent. Patented June 8, 1920.

Application filed January 30, 1919. Serial No. 274,000.

To all whom it may concern:

Be it known that we, JULIUS A. PICKENS and WALTER F. HESTER, citizens of the United States, residing at Easley, in the 5 county of Pickens and State of South Carolina, have invented certain new and useful Improvements in Elevator Mechanism, of which the following is a specification.

Our invention relates to composing machines of the general character represented in Letters Patent of the United States, as per linotype machinery, No. 436,532, dated Sept. 16, 1890.

In machines manufactured under the 15 above specified patent, the assembling block is, after being filled with the matrices and space bands to the extent of a predetermined length of line, elevated by the hand of the typographer by means of a lever or key. 20 The object of this invention is to relieve the typographer, by means of an electro-mechanical mechanism, of this labor.

In the drawing, said drawing forming a 25 part of this specification, this invention is illustrated in one embodiment which the electro-mechanical mechanism may assume, showing its relation and connection to the adjacent parts of the composing machine to which it is applied; the parts of said machine being designated by plain and exponentiated letters; while the parts of this invention are denominated by numerals, similar parts being designated by similar numerals throughout the different figures of 30 the drawing.

Figure 1 illustrates a front elevation of a sufficient portion of the original machine, to 35 carry and show our invention and its relation to the adjacent parts of said machine; Fig. 2 illustrates in detail the position of the contact points. Fig. 3 is a diametrical, longitudinal view on line AA-AA of Fig. 2; Fig. 4 is an end view on line BB-BB of Fig. 2.

40 This invention, being applied as per Fig. 1, operates in the following way:

As the assembling block I fills with the matrices and space bands, the resistant J is urged to the left step by step a distance 45 forming to the adjusted space between the contact-point 2 of the sliding-bar j's adjusting screw 2^a, and the contact-point 1^a of the sliding bar bracket pall 1; said adjusted space being equal to and predetermining the 50 length of line "set out" or composed or the

number of matrices and space-bands assembled in I.

When the desired length of line is thus attained, the electric circuit is closed by means of the above referred to 1^a and 2 coming in contact with each other.

The electric circuit being thus closed, the electro-magnet 6 6 is energized and, being granted horizontal movement, by means of the leaf-spring 7, to the right, magnetically 65 attaches itself to the continuously driven disk 8.

The instant magnetic attachment is effected between 6 and 8, the entire mechanism, as illustrated in detail by Fig. 2, 70 revolves through an arc of sufficient length to elevate by means of the crank 19 the pitman 20. 20 communicating with I, thus elevates I to the stationary guide block M. The instant I attains the position of discharge at M, j is automatically released, from the position to which it has been pressed to the left by the matrices and space bands that were assembled in I, and when so released is pulled to the right by means 75 of a spring acting through the lever J^a.

And should the provision in the original machine, or modification of the original machine, fail to instantly release j, when I attains the discharge position at M, and thereby fail to open the electric circuit at 1^a and 2, a secondary provision is provided in the form of a crank 24 attached to the hub of 19 and adjustable to the desired position or angle by means of the set-screw 25 so as 80 to raise or open the switch 23 at the desired instant.

The electric circuit being instantly opened when I attains the discharge position, 6 6 is released from magnetic attachment from 8 95 and the weight of I and appurtenances thereof descending, preparatory to being re-filled, cause the mechanism illustrated in Fig. 4 to reverse through the arc through which it revolved to elevate I, and these 100 movements being repeated at intermediate intervals automatically, the main object of this invention is accomplished.

The electrical wiring of this invention is arranged so that the elevating mechanism 105 may be operated by the hand or the foot of the typographer, when automatic operation is not desired.

That the shock resulting from the magnetic attachment of 6-6 to 8 be eliminated, 110

8 is driven by means of a belt 18 constructed of elastic material running in the groove 9 and being driven from a pulley placed on the shaft a^{33} of the original machine.

5 That the wiring may communicate with 6—6 from the other parts of the circuit, the shaft 11 is provided with a tubular opening 17 horizontally through its central portion.

10 and 14 are set screws, 16 is a washer 10 and 15 a sleeve. 10, 14, 15 and 16 permit horizontal adjustment on 11 of the driven mechanism 8 and 9 relative to coördinate position of the driving mechanism a^{33} of the original machine.

15 One embodiment of this invention being as herein illustrated, we would have it understood that modifications thereof embracing similar electro-mechanical principles as those herein described and illustrated, be 20 contemplated as coming within the scope of claims appended hereunto.

We claim:—

1. In a typographical machine, an assembly elevator adapted to receive a series of 25 matrices, a resistant yielding before said matrices, and means acting to raise said elevator when said resistant has yielded in a

predetermined amount before said matrices, substantially as specified.

2. In a device for automatically raising an assembly elevator, a fixed contact point, a yielding resistant carrying a second contact point, an electric circuit closed by the contact of said contact points, and means set in operation thereby to raise said elevator, substantially as described.

3. In a device for raising an assembly elevator, a constantly rotating disk of magnetic material, a rock shaft, a clutch disk on said shaft adjacent said rotating disk, 40 electro-magnets mounted on said clutch disk and adapted when energized to secure it to said rotating disk, means operated by said rock shaft to raise said elevator, an electric circuit acting to energize said magnets when closed, and means acting to close said circuit when said elevator contains a series of matrices of a predetermined length, substantially as described.
